UNITED STATES PATENT OFFICE.

MAURICE J. ACHOR, OF MARION, INDIANA.

DESIGN FOR A FLAG, PENNANT, CURTAIN, TABLE-COVER, PILLOW, POSTER, OR AN ARTICLE OF SIMILAR NATURE.

53,429.

Specification for Design.

Patented June 17, 1919.

Application filed March 28, 1919. Serial No. 285,936. Term of patent 7 years.

To all whom it may concern:

Be it known that I, MAURICE J. ACHOR, a citizen of the United States, residing at Marion, in the county of Grant and State of Indiana, have invented a new, original, and ornamental Design for Flags, Pennants, Curtains, Table-Covers, Pillows, Posters, or Articles of Similar Nature, of which the following is a specification, reference being had to the accompanying drawing, forming part thereof.

The figure is a plan view of a flag, showing my new design.

I claim:

The ornamental design for a flag, pennant, curtain, table cover, pillow, poster, or an article of similar nature, as shown.

MAURICE J. ACHOR.
